BUILDING PRODUCT AND METHOD OF
MAKING THE SAMEThomas Robinson, New York, N. Y., assignor to
Lancaster Asphalt, Inc., New York, N. Y., a
Corporation of DelawareOriginal application July 10, 1928, Serial No.
291,638. Divided and this application November
23, 1929. Serial No. 409,300

23 Claims. (Cl. 154—2)

This invention relates to roofing elements and is concerned more particularly with a novel shingle which is of great durability and resistance to the action of the elements, and to a method 5 by which such products can be produced rapidly, cheaply and uniformly.

The roofing elements of this invention are preferably of tapering thickness and have the form either of individual shingles or of the strip shingle now well-known in the roofing article. By 10 such tapered construction, the new shingles may have a substantial thickness at the butt so that they cast a considerable shadow and thus produce a roof of attractive appearance, and at the same time may be laid in overlapping courses 15 with the shingles in the several courses lying flat without bulging or being bent.

The new shingles are composed primarily of fibrous material bound together by a plastic substance capable of hardening, and preferably consist of a plurality of layers of such ingredients, differing among themselves in the relative proportions of fibre and plastic present but produced in such manner that the several layers are combined into a unitary structure. Because of the 20 variations in the amounts of fibre present in the various layers, the layers differ in physical characteristics and I take advantage of these differences in the production of products for different 25 uses.

The fibrous materials used are of a wide variety and include, for example, asbestos, vegetable fibre, such as cocoanut fibre, wool felt scrap, bagasse and the like, with which in some 30 instances may be mixed suitable amounts of a filler such as clay. Waste paper, wood fibre, chopped hay may also be employed. The plastic substance that I employ is one capable of resisting the action of the weather, and I have found that bituminous products, such as asphalt 35 of a melt point capable of withstanding solar heat, is satisfactory both for the above reason, and because it is easily worked, and available at relatively low cost. For some purposes, it 40 may be desirable to mix with the fibre and plastic compound amounts of finely divided solid material, such as cinders and the like to reduce the cost.

In the production of the new shingles by the 45 method of the invention, I employ a plurality of sheet forming devices or calenders, arranged in a line with each one delivering a sheet to the one next succeeding. To the first of these 50 devices there is supplied a mixture of fibre and plastic in proper proportions to produce a layer

of the desired physical characteristics to form one face of the finished product, and a web of this material is sheeted out by the first calender and delivered to the one next in series. The second device operates on a mixture of fibre 60 and plastic of different proportions from the first mixture and sheets out a web of the second mixture, at the same time applying and uniting it to one face of the web first formed. These sheeting-out operations are performed while the 65 plastic material is relatively fluent so that the formation of the sheets and their union may be effected without difficulty. These steps are repeated in the later devices to build up a sheet of as many layers as may be desired, though 70 it is usually preferable to build up the final sheet of an uneven number of layers, the center layer or core containing a relatively small proportion of fibres to plastic, while the outer layers on each side thereof contain successively greater 75 amounts of fibre until the facing sheets are reached, where the greatest amount of fibre is present. In the center layer or core, there may be present a substantial amount of ingredients 80 cheaper than the fibre elsewhere used, examples 80 of such cheaper ingredients being waste paper, cinders, clay, wood fibre and the like.

In the production of shingles, a sheet is built up to the desired thickness by the devices described, and this sheet is then led to rotary 85 molding devices which receive the sheet between them and cooperate to vary the shape and thickness of selected portions thereof by the application of pressure and then excise such formed 90 portions from the sheet to form the finished 90 product. These cooperating drums have cooperating mold cavities in their faces by which the shaping operations are performed, and by the use of drums having cavities of different contour, products of different sizes and shapes, as desired, 95 may be readily formed from the sheet.

The roofing elements made in the manner described are preferably produced from a sheet having three or five layers, the central layer or core being more fluent and less stiff than the outer layers either by reason of including less fibre or solid material and more plastic, or plastic having a lower melt point. The outer layers include increased proportions of fibre to plastic, the outermost layers including the greatest 100 amount of fibre so that they are firmer and more rigid than the layers between them. The shingles are finished by the application of granular surfacing material applied either to the 105 finished shingles or to the sheets before the 110

shingles are formed therefrom, the use of the greatest amounts of fibre in the outermost layers preventing the complete submergence of the granules in the sheet when subjected to pressure.

5 For a better understanding of the invention, reference may be had to the accompanying drawings, in which:

Fig. 1 is a view in side elevation diagrammatically illustrating apparatus for practicing 10 the new method of producing the new shingles;

Fig. 2 is a similar view illustrating a modified form of apparatus for the same purpose;

Figs. 3 and 4 are sectional views of a sheet material and the novel roofing element produced 15 therefrom;

Figs. 5 and 6 are sectional views similar to Figs. 3 and 4 but showing a modification;

Figs. 7 and 8 are plan views of two forms of 20 strip shingle which may be produced by the new process.

Figs. 9 and 10 are plan views of two forms of individual shingles which may be produced by the new invention;

Figs. 11, 12, and 13 are edge views of three 25 different types of shingle embodying the invention; and

Figs. 14 and 15 are sectional views of sheet material which may be used in making the new shingles.

30 Referring now to the drawings, the sheet material illustrated in Figs. 3 and 5 is shown to consist of a plurality of layers united face to face. The sheet shown in the first of these figures consists of five such layers, while the other sheet is 35 made up of three layers. In each instance the sheet is coated on both faces and on one of these faces wear material such as crushed slate or the like is shown partially embedded in the coating.

40 The materials of which the layers of this sheet material are made consist of fibre, and a plastic substance capable of hardening. Fibrous materials suitable for the purpose include asbestos, cocoanut fibre, wood fibre, bagasse, wool felt scrap 45 and other similar products of that character. Various plastic substances may be used but I prefer to use those of a bituminous character, such as asphalt. The asphalt used is one having a melt point such that the asphalt is capable of 50 withstanding solar heat. The sheet material may be made up of these ingredients in varying proportions and I prefer to build up a sheet material by joining together layers sheeted out of the mixtures of fibre and plastic, the proportions 55 of these ingredients varying in the different layers which form a single sheet. In some instances it may be desirable to add filling material, such as clay and waste paper, and for some purposes it is satisfactory to incorporate finely divided solid 60 material, such as asbestos sand, infusorial earth, cinders, crushed rock, crushed slate and the like.

65 In preparing the sheet material, I prefer to employ a central layer or layers in which there is a considerably lower amount of fibre present than in the outer layers which form the facings of the sheet, and a typical sheet such as that illustrated in Figure 3 may consist of five of these layers in which those designated 10 and 11 constituting the outer facing layers will contain up to 70 about 50% of fibre and the remainder asphalt, while those designated 12 and 13 contain about 25% of fibre with the remainder asphalt, while the central layer or core 14 contains less and cheaper fibre, a filler, and the remainder asphalt. 75 Preferably the outer layers or facings are rela-

tively thinner than the central layer or core, and these outer layers have a high fibre content to form what amounts to a protective jacket over the material which lies between them. Sheet material to be converted into roofing elements 80 by a shaping and cutting process, preferably includes asphalt of a melt point such that it will remain plastic long enough to permit the final shaping operations to be carried on with facility. 85

As an example of a mixture which is suitable for use in the central layer or core, I may employ asphalt, cinders and paper, a suitable mixture including 80 pounds of paper, 90 pounds of cinders and 150 pounds of asphalt. The paper is first steamed and pulped in a mixer, then mixed 90 with the proper proportion of dry cinders and the mass ground in a suitable mill until the cinders are fairly fine and graded. This mixture is then put through a dryer, preferably of the rotary steam-heated type, to remove moisture and then conveyed to a pug mixer where the proper amount of asphalt is added.

This mixture of paper, cinders and asphalt affords numerous advantages when used as the central layer or core of a sheet to be converted into 100 shingles, because the ingredients are of low cost, available in large quantities everywhere, and a shingle produced from them is semi-rigid, due to the presence of the cinders, is practically non-absorbent, fairly light in weight, and a good insulator. In addition, such a shingle is resistant to fire and nails can be driven through it without the necessity of preforming holes. This mixture when used as the core or central layer is 105 capable of being molded to give the shingle the desired final shape and when so used the fibrous outer layers may be relatively thin.

In the sheet illustrated in Figure 5, the central layer 15 contains the relatively lower proportion of fibre and the two facing layers 16 and 17 110 contain higher amounts of fibre and preferably up to about 50%. On both sheets coatings designated 18 and 19 are applied, these coatings being a waterproof substance, preferably asphalt of the desired melt point. In the coating 18 in Figure 115 3 there is partially embedded a layer of granules 20 which may be crushed slate, crushed rock and other similar products ordinarily used to provide wear surfaces, while the opposite face of this sheet may have a coating of a non-stick material such as talc or the like applied over the coating. In the product shown in Figure 5, the granular material 20 is applied to the coating 19 120 and partially submerged therein, the granular material shown in these two figures being applied in different manners whereby in one instance the granular material projects beyond the coating, while in the other the surfaces of the granules lie substantially flush with the coating. The method by which the granular material 125 is applied to produce these different effects will be made clear hereafter.

In the production of the new sheet material, the plastic mixtures are preferably made up in advance of actual use, as for instance, by pulverizing the solid asphalt to the desired fineness and then mixing this asphalt powder with the desired amount of fibre. The mixture is then heated to render the asphalt fluent and this mixture conveyed to a device by which it may be formed into 130 a sheet. To build up a finished sheet, I utilize either the apparatus illustrated in Figure 1 or Figure 2.

In the apparatus shown in Figure 1, there are 135 a plurality of stands 21 of rolls arranged pref-

erably three high in a stand. The rolls are power driven and the central and top rolls 22 and 24 preferably are cooled and operate at a higher speed of rotation than the bottom roll 23 which is heated. The rolls are spaced apart a distance which is dependent upon the thickness of the sheet to be formed thereby. The plastic mixture is delivered to the stand by a conveyor generally designated 25 and of any suitable construction. 5 This plastic mixture is discharged into a feeding trough 26 which maintains a supply of the mixture in contact with the middle roll 22 and the bottom roll 23. These rolls rotate in the direction shown by the arrows and the action of the 10 rolls is to draw plastic mixture from the supply through the space between the roll faces. The roll 22 carries with it a layer of the mixture designated 27, and this layer is carried around the face of the roll and passes between that roll 15 and the upper roll 24. By reason of the rolls 22 and 24 being rotated at a higher speed than the roll 23 the action of the stand is to discharge the sheet 27 having a thickness determined by the spacing between the rolls 22 and 24, and this 20 sheet which constitutes one of the outside layers of the finished product, is then led to the next stand.

In this stand there are central and top cooled rolls moving at one speed of rotation and a bottom heated roll moving at a slower speed. A 30 mixture of the desired proportions is delivered by the conveyor 28 to the trough 29 and a sheet 30 is formed, which is carried around the middle roll 31 and applied to the under face of the sheet 35 27 as the two sheets pass between the middle roll 31 and the upper roll 32. This formation of a sheet and its application to the lower face of a built-up sheet previously formed is continued throughout the apparatus until in the apparatus 40 as shown in Figure 1 there is produced a final sheet 33 made up of five layers and similar to that shown in Figure 3. The character of the sheet will, of course, depend upon the proportions of the fibre and plastic material occurring in the 45 several layers thereon, but preferably the sheet will consist of central layers in which there is a relatively small amount of fibre and two outer layers on each face in which the proportion of fibre to asphalt is relatively high. Also, it is 50 preferable to form such a sheet with a core 14 somewhat thicker than the other layers and having a lower amount of fibre, while the two outer layers 10 and 11 are relatively thin and contain a much larger amount of fibre. The facing layers 55 may be of substantially uniform thickness.

This sheet is capable of use for many purposes just as it emerges from the final stand of rolls but for roofing and other construction purposes, it is preferable to coat its opposite faces with a 60 thin layer of asphalt. To apply this coating, there is provided any suitable mechanism, such as a discharge nozzle 34 delivering asphalt in fluent condition upon the upper face of the sheet, the nozzle 34 having a plurality of orifices to insure that the entire face of the sheet will be covered. Beyond the nozzle 34 are placed rolls 65 35 and 36 preferably maintained at a suitable temperature to work the asphalt properly. The lower roll 36 enters a trough or vat 37 in which asphalt is maintained in fluent condition and this roll picks up asphalt and delivers it to the under face of the sheet 33. The two rolls 35 and 36 thus apply an asphaltic coating to the sheet emerging from the last stand of rolls.

If the sheet is also to receive a facing of wear

material, this can be accomplished by discharging granular material on the upper face thereof from the discharge mechanism 38, which may be of any ordinary type. The sheet with this granular layer thereon then passes beneath a hollow roll 39 through which cooling water may flow, this roll serving to embed the granular material partially in the coating and also to give the coating an initial set. The sheet then passes around another roll 40 of similar construction, so arranged that the sheet reverses direction and moves with that surface uppermost which is coated but carries no granular material. To this stretch of material a non-stick material, such as talc may be applied, a suitable distributing mechanism 41 of any ordinary type being employed for that purpose. The sheet now passes around a cooling roll 42 which forces the talc into the coating to complete the application of the talc and give the coating an initial set, and from the roll 42 the sheet passes to molding drums 43 and 44 to convert the sheet into shingles.

These drums have cooperating mold cavities 45 and 46 in their faces, arranged if desired, so as to vary the thickness of the sheet at different points and to shape and consolidate the layers. These molding cavities are also defined by cutting edges of appropriate form which cooperate to cut the shaped portions from the sheet so that as the sheet passes through the molding drums 100 individual roofing elements 47 are discharged therefrom upon a sloping platform 48.

In the apparatus as shown in Figure 2, the same principles of operation are employed, but the apparatus is modified in certain respects to vary the type of coating that would be produced. In this apparatus, there are a plurality of stands of rolls 21 similar to those used in the type of apparatus previously described, and the plastic material is delivered to the first stand of rolls by a conveyor 25 discharging into a trough 26 which maintains a supply of material in contact with the middle roll 22 and the upper roll 24. This plastic material is sheeted out by the action of the 110 rolls and travels around the face of the middle roll in a manner previously described. Contacting with the outer surface of the sheet as it moves around the surface of the middle roll is a coating roll 49 resting lightly in contact with the sheet, 115 and also contacting with a roll 50 which lies partially in a trough or vat 51 containing the coating material. The roll 50 picks up coating material from the vat 51 and transfers it to the surface of the roll 49 which in turn applies it to the surface of the sheet being carried around the 120 surface of the roll 22.

Extending from end to end of the stands of rolls is an endless conveyor belt 52, which passes around guide rolls 53 and 54 at its ends. This 135 conveyor belt may be a canvas webbing or a fine wire mesh and its upper stretch passes between the middle and lower rolls 22 and 23 of the several stands. As the first layer 27 is formed by the rolls of the first stand, this layer is carried along 140 on the surface of the belt to the next stand, where another layer sheeted out of plastic and fibrous material is applied to its upper face. The sheet is built up in the manner previously described through the successive action of the stands of 145 rolls and between each pair of rolls the sheet produced therein is supported on the surface of the endless belt. As previously described, a layer of coating material is applied to one surface of the sheet formed in the first stand of rolls by the roll 150

49 and this sheet, which is to form one of the faces of the final product, preferably includes a relatively high amount of fibre with respect to the plastic present. Immediately after the coating is applied, the granular wear material is also applied and for this purpose granular material may be discharged from a distributing mechanism 55 upon the upper surface of the conveyor belt 52 before that belt contacts with the sheet 27. 5 This layer of granular material is carried along by the conveyor to a point where the sheet and the conveyor move between the rolls 22 and 23 and at that point the granular material is partially embedded in the coating by the action of 10 the rolls. The coated layer with its outer facing of granular material passes through successive stands of rolls to receive and be united to the successive plastic layers formed by these devices. In this form of the apparatus, the top roll of each stand is preferably slow and heated while the two bottom rolls are preferably cooler and driven at a higher speed.

25 The sheet emerging from the last stand of rolls shown in Figure 2 consists of five layers made up of plastic and fibre and it has a coating of asphalt on its under surface together with a layer of granular wear surfacing. The upper face of the sheet may now be finished by the application of a layer of coating material and for this purpose a pair of rolls 56, 57 are provided, the roll 56 running partially in a vat of coating material and delivering that material to the surface of the roll 57, which lies lightly in contact with the upper surface of the sheet. 30 Beyond the roll 57 a finishing material may be applied if desired as, for example, talc, which may be delivered on the outer surface of the coating by a suitable distributing mechanism of any well-known type generally indicated at 58. Beyond this distributing mechanism, the sheet passes under a roll 59 which smooths out the coating and embeds the talc or similar material therein, and the sheet may then be converted into shingle units by being delivered to the molding drums 43 and 44 previously referred to.

45 The molding drums have knife edges defining their mold cavities and the shape of these cavities determines the shape of the finished product. In the manufacture of tapered shingles, molding drums are used which act on the sheet to shape selected portions thereof into individual units or shingles and then sever the sheet along the outline of the units. For example, the five layer sheet illustrated in Figure 3, when passed through the molding drums, may be converted into shingles of a cross-section similar to that shown in Figure 4, while shingles formed of the three layer sheet of Figure 5 have a cross-section similar to that shown in Figure 6. The sheet is delivered to the molding drums with the plastic ingredient still sufficiently fluent to permit the drums to perform the operations described. Also the plastic material used in the core is sufficiently plastic so that it will flow under the application of pressure by the drums and assume the desired tapering form, the outer layers to a greater extent preserving their original thickness. Due to the forming operations 50 performed on the sheet to convert it into shingles, it will be observed that there is a greater proportion of fibrous material to plastic at the thin end of the tapered shingles than at the thick, due to the greater amount of core material at 55 the thick end. Similarly, the amount of fibre

increases from the core outwardly toward either face.

5 By the use of suitable molding drums, individual shingles of rectangular form such as that designated 60 may be produced, or the individual shingles may have other shapes such as that numbered 61. Shingle 61 has its side edges converging toward the thick end and when this shingle is laid with others in the usual courses, the shingles contact laterally at their thin ends while at their thick ends, the side edges lie spaced apart in the ordinary manner.

80 10 The new shingles may also be made in the usual strip-shingle form 62 or in other forms such as that designated 63, in which the cutouts 64 are of wedge-shape instead of having their sides parallel.

85 15 Instead of the tapering form shown in Figures 4 and 6, the shingles may be made in other shapes, such as those shown in Figures 11, 12, 13. Shingle 65 has one flat face 66 and the end edges 67 and 68 are inclined thereto. Shingle 69 has a uniform thickness for part of its length and a tapering thickness for the remainder, while shingle 70 is similar to shingle 69 except that the 90 20 butt end has a different type of edge.

95 25 In any of these shingles, the action of the cutting edges on the molding drums causes the outer layers of the sheets to be forced into the central layers and to meet along the extreme 100 edges of the shingles. As these outer layers are highly fibrous, the finished product is one in which the more fluent inner layers are protected by the outer fibrous layers both along the 105 faces of the shingles and along at least a pair 110 of opposite edges thereof. Where the shingle is cut along all side edges from a sheet by the action of cooperating knife edges, the more fluent inner material will be completely enclosed over both faces and along all edges by the more fibrous 115 outer layers, and these layers thus add strength to the shingles and prevent displacement of the 120 core layers under pressure. The shingle therefore has what amounts to an encasing jacket in which a high proportion of fibre is present, 125 but this is accomplished without using felt, paper, or similar felted fibrous material which is preformed prior to its use in the present apparatus.

130 130 In the shingle shown in Figure 3, the granular material 20 has been applied by the apparatus shown in Figure 1. The sheet has first been formed and then coated and a layer of granular material applied to the surface thereof. Since this granular material is not subjected to severe 135 pressure after its application other than that applied by the molding drums, the granular material is only partially submerged in the coating and projects from the surface thereof. In the product shown in Figure 5, the granular material has been applied, in accordance with the method shown in Figure 2, to the surface of the first layer produced during the formation thereof and this granular substance has therefore been acted on by the rolls of a plurality of stands. This layer is consequently submerged to a somewhat greater extent than that shown in Figure 3, but the granules will not be completely submerged, although their upper surfaces lie substantially flush with the layer of coating material over which they have been applied.

140 145 For some purposes, as in the production of relatively cheap shingles, it is permissible to form the shingles of sheet material such as that illustrated in Figures 14 and 15. In the material 150

shown in Figure 14, the central layer 71 has the greater amount of fibre and forms a reinforcing member which stiffens the outer layers 72 containing relatively less fibre. The outer layers 5 have a waterproof coating 73 of asphalt. The sheet material in Figure 15 consists of a layer 74 containing more fibre, and a layer 75 containing less fibre, the faces of the sheet having the waterproof coating 76.

10 While I have described this sheet material as made up of a plurality of layers, which are illustrated in the drawings as distinct from one another, it is to be understood that in the finished product, these layers do not have any separate 15 existence but are united into a unitary sheet in which there is no well defined lines of demarcation. The plastic material used in the different layers is preferably of the same melting point, except in some instances a lower melt 20 point may be used in the core or central layer, but in any event these sheets are united face to face in the apparatus while the plastic material is still somewhat fluent, so that a perfect union between layers is accomplished. In the drawings, these layers have been shown as separate 25 and distinct for purposes of illustration, but in the finished product they merge together so that the layers can be distinguished only by the varying amounts of fibre present therein, and by 30 somewhat different physical characteristics of these different layers resulting from such differences in fibre content. To produce a sheet material suitable for formation into shingles, I prefer to employ a sheet made up of an odd number 35 of layers, with the outer layers relatively thin and containing the higher proportions of fibre, but for a sheet material to be used without further treatment as a roll roofing or siding material, various distribution of fibre and plastic may 40 be employed, of which examples have been given.

This application is a division of my co-pending application Serial No. 291,638, filed July 10, 1928.

I claim:

- 45 1. A tapered shingle comprising a hardened plastic substance and unfelted fibre, the proportion of fibre to plastic substance varying from end to end of the shingle, with the greatest proportion of unfelted fibre being near the thin end.
- 50 2. A tapered shingle comprising hardened plastic substance and unfelted fibre, the shingle including facing layers of substantially uniform thickness and a core of tapering thickness from one end to the other, the layers and core being 55 distinguishable by reason of the varying amounts of plastic substance and unfelted fibre therein.
- 60 3. A tapered shingle comprising a plurality of intimately bonded layers respectively formed of different mixtures of hardened plastic substance and unfelted fibre, the shingle including a core relatively low in fibre content, and layers forming opposite faces of the shingle and containing a greater proportion of unfelted fibre than the core.
- 65 4. A tapered shingle comprising a core of tapering thickness from one end to the other, and including hardened plastic material and unfelted fibre, and a layer of substantially uniform thickness on each face of the core made up of hardened plastic material and unfelted fibre and 70 distinguishable from the core in having a greater proportion of fibre.
- 75 5. A shingle comprising a core and a layer formed of a mixture of unfelted fibre and hardened plastic material on each face of the core.

6. A shingle comprising a core and a layer of unfelted fibre and hardened plastic material on each face of the core, the layers meeting along at least a pair of opposite edges of the core.

7. A shingle comprising a core and a jacket formed of a mixture of unfelted fibre and hardened plastic material completely encasing the core. 80

8. A strip shingle comprising a plate-like core and a jacket formed of a mixture of unfelted fibre and hardened plastic material on each face of the core, portions of the core and jacket being cut out along one edge to define a plurality of spaced tabs. 85

9. A shingle comprising a core including hardened plastic material and facing layers including an intimate mixture of hardened plastic material and unfelted fibre on opposite faces of the core. 90

10. A shingle which comprises a central core of asphalt, cinders, and paper pulp, and outer facing layers including unfelted fibrous material impregnated with asphalt. 95

11. A shingle which comprises a central core of plastic material, fibrous material and finely divided solids, and outer facing layers on the core made up of an intimate mixture of plastic material and unfelted fibrous material. 100

12. The method of producing roofing shingles which comprises, continuously forming under pressure a sheet composed of a plurality of superposed intimately bonded layers of dry mixtures of unfelted fibre and hardenable plastic material, at least one of the said layers having a smaller proportion of unfelted fibre to plastic material than the other layers, applying pressure to the sheet thereby forming a shingle tapering in thickness from one end thereof to the other, and cutting the thus-shaped shingle from the sheet. 115

13. The method of producing roofing shingles which comprises, forming under pressure a continuous sheet of a non-aqueous mixture containing unfelted fibre and a thermoplastic material which is hard at normal atmospheric temperature, the said mixture being of uniform pre-selected fibre content, thereafter sealing to at least one face of the said sheet a layer of a mastic containing unfelted fibres and a thermoplastic substance in preselected proportions so selected that the said layer is more fluent and less stiff than the said sheet, thereafter shaping under pressure the resultant composite sheet thus formed in a manner to adjust the thickness thereof to form a tapered shingle, and cutting the said shingle from the sheet. 120

14. The method of producing roofing shingles which comprises forming under pressure a continuous sheet made of a substantially dry mixture containing unfelted fibre and a fluent thermoplastic material capable of hardening, the said mixture being of uniform preselected fibre content, sealing under pressure to each face of the said sheet, in the substantial absence of water, a layer made of a second intimate mixture containing unfelted fibre and a fluent thermoplastic material, thereby forming a composite structure having a middle core or layer which is more fluent and less stiff than each of the pair of outer layers to which it is intimately bonded, shaping the composite structure, and cutting the shaped portions from the sheet. 125

15. A method of producing roofing elements which comprises uniting under pressure a sheet composed of an intimate mixture of unfelted fibre 130

145

- and plastic material and a layer of a mixture of unfelted fibre and plastic material having a lower ratio of unfelted fibre to plastic material than that of the said sheet, applying a coating of 5 surfacing material to a face of the resultant composite sheet, and cutting elements of selected size from the sheet.
16. A method of producing roofing elements which comprises uniting under pressure upon a 10 sheet composed of an intimate mixture of unfelted fibre and plastic material, a plastic layer of a mixture containing unfelted fibre and a plastic material capable of hardening, the plastic layer having therein a lower ratio of unfelted fibre to plastic material than the first-named layer, affixing a layer of surface material to at 15 least one of the surfaces of the resultant composite sheet, varying the thickness of selected portions of the sheet, and cutting from the sheet 20 the said portions.
17. A method of producing roofing elements which comprises uniting under pressure upon a layer composed of an intimate mixture of unfelted fibre and plastic material, a second layer 25 of a mixture of unfelted fibre and hardenable plastic material, which second layer has a lower percentage of unfelted fibre present therein than the first-named layer, then uniting under pressure to the last-named layer a third layer of a 30 mixture of unfelted fibre and plastic material in approximately the same proportions as they are present in the first-named layer, shaping selected portions of the resulting composite sheet by the application of pressure and cutting the 35 shaped portions from the sheet.
18. The method of producing roofing shingles which comprises, successively applying under pressure to a sheet composed of a dry mixture of unfelted fibre and hardenable plastic material, a plurality of strata of dry mixtures of unfelted fibre and plastic material of regulated thickness, at least one of the last-named dry mixtures having a smaller proportion of unfelted fibre 40 to plastic material than that of the layers respectively superposed upon either side thereof, applying pressure to the sheet thereby forming a shingle, and cutting the shingle from the sheet.
19. The method of producing roofing shingles 45 which comprises, successively applying under pressure to a sheet composed of a dry mixture of unfelted fibre and hardenable plastic material, a plurality of strata of dry mixtures of unfelted fibre and plastic material of regulated thickness, at least one of the last-named dry mixtures having a smaller proportion of unfelted fibre to plastic material than that of the layers respectively superposed upon either side thereof, applying pressure to the sheet thereby forming a shingle, and cutting the shingle from the sheet.
20. A shingle which comprises a pair of outer 50 facing layers containing unfelted fibre and plastic material in which the fibre does not substantially exceed 50% of the material forming the layer, subjacent layers each containing smaller percentages of fibre to plastic material than that of the outer facing layers, and an inner core containing still smaller percentages of unfelted fibre together with plastic material and an inorganic filler.
21. A shingle which comprises a pair of outer 55 facing layers containing unfelted fibre and plastic material in which the fibre is present in not greater than 50% of the said layers, subjacent layers containing around 25% of unfelted fibre together with hardenable plastic material, and an inner core containing a small amount of unfelted fibre together with plastic material and an inorganic filler.
22. A shingle which comprises a pair of outer 60 facing layers containing unfelted fibre and plastic material in substantial proportions, subjacent layers each containing smaller percentages of fibre to plastic material than that of the outer facing layers, and an inner core containing still smaller percentages of unfelted fibre together with plastic material and an inorganic filler, at 65 least one of the said outer facing layers being impregnated with a hardenable water-proofing material.
23. A shingle which comprises a pair of outer 70 facing layers containing unfelted fibre and plastic material in substantial proportions, subjacent layers each containing smaller percentages of fibre to plastic material than that of the outer facing layers, and an inner core containing still 75 smaller percentages of unfelted fibre together with plastic material and an inorganic filler, at least one of the said outer facing layers having an asphalt coating, and a layer of wear-resistant 80 surfacing material partly submerged in the said asphalt coating.
